CLAIM

We claim the ornamental design for a snorkel, as shown and described.

DESCRIPTION

FIG. 1 is a bottom and right and rear side perspective view of a snorkel,

FIG. 2 is a right elevation view thereof,

FIG. 3 is a left elevation view thereof,

FIG. 4 is a rear elevation view thereof,

FIG. 5 is a front elevation view thereof,

FIG. 6 is a bottom plan view thereof,

FIG. 7 is a top plan view thereof; and,

FIG. 8 is a bottom and left and rear perspective view thereof.

All broken lines illustrate portions of the snorkel to which the design is applied that form no part of the claim.
